Patented July 23, 1912.

UNITED STATES PATENT OFFICE.

DARIUS N. BARRETT, OF DETROIT, MICHIGAN; LEE E. GRANT ADMINISTRATOR OF
SAID BARRETT, DECEASED.

SAFETY-RAZOR.

1,033,373.

Specification of Letters Patent. Patented July 23, 1912.

Application filed May 3, 1911. Serial No. 624,758.

To all whom it may concern:

Be it known that I, DARIUS N. BARRETT, a citizen of the United States, residing at Detroit, in the county of Wayne and State of Michigan, have invented new and useful Improvements in Safety-Razors, of which the following is a specification.

This invention relates to safety razors and the object of the invention is the provision 10 of a device of this character whereby the blade may be readily detached from and attached to the back and be used in the manner of the ordinary straight blade razor.

A further object of the invention is the 15 provision of a novel safety guard adapted to be used in connection with this razor and which is also readily connected to and disconnected from the razor back.

Further objects of the invention will appear 20 as the following specific description is read in connection with the accompanying drawing, which forms a part of this application, and in which:—

Figure 1 is a side elevation of the razor. 25 Fig. 2 is an end elevation. Fig. 3 is a side elevation of the blade clamp. Fig. 4 is an end elevation thereof. Fig. 5 is a side elevation of the blade. Fig. 6 is an end elevation thereof. Fig. 7 is a side elevation of 30 the back. Fig. 8 is an end elevation thereof. Fig. 9 is a side elevation of the safety guard. Fig. 10 is an end elevation thereof.

Referring more particularly to the drawing, 1 represents an ordinary handle to 35 which is pivotally secured a blade arc 2. This back has a reduced extension 3 forming a shoulder 4 and, adjacent its upper edge, is inwardly tapered, as shown at 5, and its upper edge provided with a concave 40 groove 6. Rolled upon the extension 3 and having its inner end abutting the shoulder 4 is a blade clamp 7 which is substantially U-shaped in cross section and has inwardly extending ribs 8 and converging extensions 45 9 beyond the ribs. These extensions form a channel way for the reception of the blade 10 which is slid into the channel until its inner end abuts the shoulder 4. The blade is thus removably held in position, and in 50 this manner the razor may be used in the ordinary fashion without the safety device, to be now described, although in this type

of device it will be readily seen that the shaving outfit will preferably consist of a handle back and blade clamp which is 55 adapted to hold one of the plurality of blades furnished with the outfit.

The safety guard comprises a strip of metal 11 having upon one edge a plurality of downwardly and outwardly curved teeth 60 12 and at its inner side is turned inwardly to form a rib 13 which engages in the channels produced in forming the ribs 8. In the opposite ends of the plate U-shaped hooks or clamping members 14 are formed which 65 have inward extensions 15 to engage in the channels produced in forming the ribs 8, and these hooks are adapted to snap up over the blade clamp, so as to hold the guard plate with the teeth resting approximately 70 on the edge of the blade. The ends of the teeth slightly overlap the edge of the blade so that when the blade is held at an angle to the face in shaving the teeth will engage the face and prevent accidental cutting. 75 The teeth and the guard also bear upon the blade in opposition to the direction of the pressure exerted in shaving, and therefore strain is relieved from the guard clamp to a great extent. Both the safety guard and 80 the blade clamp are of spring steel, preferably rolled into their respective outlines.

Having thus described the invention, what I claim as new is:—

A safety razor comprising a handle, a 85 back member pivoted thereto and having its upper side edges inwardly curved and its inner edge grooved, a substantially U-shaped clamping device removably mounted on the back member and having its sides conforming 90 to the sides of the back member, and provided with converging legs to clamp and fit a concave blade, a blade mounted in the clamping member and seated in the grooved back member, a safety guard, and U-shaped 95 spring hooks formed integral therewith and conforming to and adapted to clamp over the clamping member.

In testimony whereof I affix my signature in presence of two witnesses.

DARIUS N. BARRETT.
